UNITED STATES PATENT OFFICE

FRANK D. CARNEY AND RICHARD V. MCKAY, OF STEELTON, PENNSYLVANIA.

CHARGING-CAR.

1,158,982.

Specification of Letters Patent.

Patented Nov. 2, 1915.

Application filed March 4, 1914. Serial No. 822,470.

To all whom it may concern:

Be it known that we, FRANK D. CARNEY and RICHARD V. MCKAY, citizens of the United States of America, residing at Steelton, in the county of Dauphin and State of Pennsylvania, have invented certain new and useful Improvements in Charging-Cars; and we do hereby declare the following to be a full, clear, and exact description of the invention, such as will enable others skilled in the art to which it appertains to make and use the same, reference being had to the accompanying drawings, and to letters or figures of reference marked thereon, which 10 form a part of this specification.

Our invention relates to mechanism for sintering ore and other fines, and has for its object to provide a cover for any well-known type of sintering pan, which shall not only 20 operate as a cover for the ignition of the material in the pan, but shall also operate as a means for charging the pan, and means for leveling the charge in the pan before sintering.

25 Specifically, the cover is mounted on a car truck operated by suitable electrical mechanism, to which current is supplied through a trolley or otherwise, as will hereinafter be more particularly pointed out and claimed.

30 Referring to the drawings, in which like parts are similarly designated—Figure 1 is a plan view of mechanism embodying our invention. Fig. 2 is a side view thereof, having parts broken away. Fig. 3 is a vertical section on line 3—3 of Fig. 2, showing the various lever mechanisms in elevation. Fig. 4 is a section on line 4—4 of Fig. 2, and Fig. 5 is a longitudinal section showing the louver arrangement forming the bottom of 40 the charging car.

In the drawings, A is a well-known type of sintering pan provided with suitable grate bars B, and with suitably shaped ends C and D through which exhaustion takes 45 place to maintain combustion in a layer of material to be sintered on the grate B.

The pan A is mounted in any well-known manner, and may be rotated or tipped by any suitable mechanism the power of which 50 is applied to the pan through the gear wheel E. This structure forms no part of our invention, and is of a type well known in the art. Heretofore these pans have had a removable cover provided with suitable 55 burner mechanism, but there was no mecha-

nism for quickly and easily placing the cover on the pan, or for removing it when the ignition or the sintering operation was completed, and the charging of the pans, and the leveling of the charge in the pans has been 60 done manually.

According to our invention we provide a car carrying the cover, and the cover can be rapidly raised and lowered with respect to the pan when the car has been run over said 65 pan. The cover is also provided with a drop-bottom, for carrying a charge sufficient to fill the pan when dumped, said bottom also acting as leveling means for leveling the charge in the pan when in its dropped 70 position, and also acting, when raised, as the inclosing cover over the igniting means and pan. The car carries an electric motor-operated from the trolley or its equivalent, which motor also actuates mechanism for 75 raising and lowering the cover and for operating the bottom. It also carries an oil tank, a compressed air tank, and means for supplying the latter tank with air, said tanks supplying oil and air to a suitable burner 80 projecting below, or at least on a level with the dumping bottom.

The sintering pan A is located between track rails 2 and at such a height between these rails that the cover can be easily applied and removed.

The car comprises a suitable framework or body 3, of structural iron, provided at one end with a platform 4 on which is mounted the various mechanisms required 90 for the operation of the car. In the frame or body 3, is mounted an axle 5 and a driven axle 6 on the ends of which are rigidly secured the car wheels 7. The frame 3 is also provided with transverse members 3^a adjacent each end of a cover 10, and on which are mounted antifriction rollers 8 operating in channels 9 on the cover 10. Across the top of the frame 3 near each end of the cover 10 are shafts 11 and 12, each provided with 100 two levers 13 rigidly secured thereto near the sides of the cover. Each lever 13 is connected by link 14 to lugs or ears 15 on the cover.

The shaft 11 is provided at one end with a 105 downwardly inclined lever 16, and the shaft 12 is provided with an upwardly inclined lever 17. Pivoted on the end of lever 17, Fig. 2, is a rope connection 18, from which a rod, wire or rope 19 leads to a like con- 110

nection 20, pivoted to the end of lever 16, whereby both shafts 11 and 12 are caused to operate simultaneously when the rope 19 is drawn. This rope 19 is drawn by means 5 of a rope 21 whose rope connection 22 at one end is also pivoted to lever 17, and whose other end is connected to a rope drum 23 on a main operating shaft 24 mounted in the frame and extending across the platform 4.

10 Adjacent this drum 23, or made in one piece therewith is a friction member 25 of a friction band brake 26, and the two drums are simultaneously clutched to or released from shaft 24 by a clutch 27 operated by a rod 15 28, a bell-crank lever 29 and a hand lever 30.

The main driving shaft 24 has a large spur gear wheel 31 actuated by a pinion 32 of an electric motor 33 supplied with current through a trolley 34. The lift of the 20 cover 10 need be but a few inches, and it can be raised from the position shown in the drawings by means of the ropes 19 and 21 when the clutch 27 is thrown, after which it may be held in its raised position by the 25 brake 25, 26, when the clutch is disengaged.

The brake band 26 is connected to a rod 36 which is connected to a crank arm 37 on a shaft 38 provided with a lever arm 39 operated by a pedal 40, Figs. 2 and 3.

30 The cover also carries a burner 35 of the type shown in United States Patent No. 1,064,314, granted June 10, 1913. This burner is connected by a pipe 36, flexible connection 37 and line 38 to oil tank 39 on platform 4. The burner 35 and pipe 36 are supported by an angle iron 40 extending across the middle of the cover.

Air is supplied to the burner through a pipe 41 contained within the pipe 36 and 40 having a flexible connection 42 with a line air pipe 43 leading to a compressed air storage tank 44, also on platform 4, and which is supplied with compressed air through a pipe 45 from an air compressor 46 driven by an electric motor 47, also located on platform 4.

The line pipes 38 and 43 are provided with cut-off valves *o* and *a* respectively, located at the platform 4, and actuated by 50 any suitable lever mechanism, indicated at *o'* and *a'*.

The tops of the air and oil tanks are connected by a pipe *b* having a valve *c* whereby air pressure is applied on the surface of the 55 oil in the tank, 39.

The main driving shaft 24 is provided with a loose chain wheel 48 arranged to be connected to and disconnected from said shaft by means of a clutch 49 operated by 60 a rod 50, a bell-crank lever 51, a link 52 and a hand lever 53.

The bottom of the cover 10 consists of a series of louvers or sectional bottoms 61, more clearly shown in Fig. 5, each of which 65 is secured on a shaft 62 and arranged at

sufficient height above the bottom edge of the cover so that when the louvers assume the position shown in dotted lines in Fig. 5 to discharge their loads, the lower edges of these louvers or sectional bottoms will be 70 substantially in a plane with the bottom of the cover. Each shaft 62 is provided with an upwardly inclined lever 63 at one end thereof and between the frame and the cover and all of these levers 63 are connected 75 to a rod 64, whereby the louvers 61 may be simultaneously operated.

Connected to the rod 64 at 65 is a rope 66 secured to a drum 67 similar to drum 23, and having a like friction brake 68 and a clutch 69 for connecting and disconnecting the drums from the driving shaft 24. This clutch is operated by a rod 70, a bell-crank lever 71, a rod 72 and a hand lever 73. The brake band for brake 68 is similar in construction and operation to brake band 26, and is connected to a rod 74, Fig. 3, which is connected to a crank 75 on a rod 76 provided with a lever arm 77 that is actuated by pedal 78, this mechanism being substantially a duplicate of the clutch, drum and brake mechanism on the opposite end of shaft 24.

79 is a controller, controlling the supply current to the motor 33.

The louver mechanism or drop bottom for the cover 10 is held raised by rod 64, rope 66, drum 67 and brake 68.

The car is run to the mixing plant, or other source of supply of material to be sintered, and the cover is loaded with said material, which is preferably but not necessarily struck off level across the top of the cover. The clutch 49 is thrown to clutching position so that the motor 33 will drive 100 the car with the cover suspended in raised position therein. Upon arriving in position over the pan A the clutch is disconnected and brake 26 is released, thereby permitting the entire cover 10 with its contained load to be lowered onto the pan A. The clutch 68 is then released, and the weight of the load on the louver bottom 61 will cause the louvers to turn down into the dotted line position shown in Fig. 5. The 115 cover is then slightly raised and traversed back and forth, so that the depending louver bottom 61 will strike the charge level. The extent of this movement need not be greater than the width between the leaves 61. The 120 cover 10 is then lowered again onto the pan and the louvers raised into the position shown in full lines in Fig. 5. Suction is then placed on the pan A through its open ends. Then the valves *o* and *a* are opened, 125 and compressed air and oil are supplied to the burner 35 and ignited. The ignition of the material to be sintered takes place in about a minute, more or less, after which the supply of fuel and air to the burner is 130

cut off, the cover lifted clear of the pan, and the car is driven again to the mixing plant for another charge, while the combustion of the charge in the pan is maintained and the sintering operation completed by the suction at the ends of the pan.

Heretofore it has been difficult to place the charge in the sintering pan so that it would have a uniform compactness. When the pan was loaded by shoveling the material into the pan the charge was compacted more in one place than in another, as was also the case when the charge was delivered to the pan from a hopper. The result was that when the pan was placed under suction for sintering the charge, the air would follow the course of least resistance through the less compacted places and bore through at these points, leaving a large portion of the charge unsintered. The problem of obtaining some practicable method of charging these pans that is sufficiently economical to be performed for commercial purposes has occupied the attention of engineers for some time. We believe that we have successfully solved this problem for commercial purposes; instead of obtaining a cake from the pan containing only from 20% to 40% of sintered material, we obtain a cake that contains from 60% to 90% of sintered material, and this is due to our method of charging. This method consists in moistening the charge to about the consistency of molder's sand, subdividing it, and dropping all portions of the subdivided charge into the pan from the same height, so that the same degree of compactness will be caused by the fall of the subdivided portions onto the sintering grate or plate, and leveling the surface.

The distance that the subdivisions of the charge fall should preferably be small, say one foot, more or less.

We claim—

1. In combination, a car, power mechanism on the car for propelling it, a sintering pan cover suspended in the car, and mechanism for moving the cover to and from a sintering pan.

2. In combination, a wheeled car, a cover mounted therein and having an open top and a dumping bottom, and mechanism between the cover and car for lowering and raising the cover to and from a sintering pan, and mechanism for operating said bottom.

3. In combination, a car body having a louver charge-supporting bottom, means to operate the bottom to dump a charge, a burner beneath the bottom, means to supply combustible and combustion air to the burner, and means to lower said body onto and raise it from a sintering pan.

4. In combination, a car, power driving mechanism therefor, a sintering pan cover

mounted therein, a dumping bottom for said cover and mechanism for moving said bottom actuated by the power mechanism.

5. In combination, a power driven car and a sintering pan cover mounted therein and having an open top and a dumping bottom, mechanism for lowering and raising the cover to and from a sintering pan operated by said power driving mechanism, and mechanism for moving said bottom also operated from said power driving mechanism.

6. In combination, a car, a sintering pan cover mounted therein and a sectional dumping bottom in the cover the sections of which, when in dumped position, are arranged to strike the charge level.

7. In combination, a carriage, a sintering pan cover suspended in the carriage, mechanism for moving the cover onto and from a sintering pan, a louver bottom for the cover for sustaining a charge to be sintered, an ignition device below the bottom and supported by the cover, the edges of the louvers of said bottom when in dumped position substantially in the plane of the bottom of the cover, means for raising the louvers and means for moving the carriage.

8. In combination, a carriage, a motor thereon, a trolley to supply electric current to the motor, a main driving shaft on the carriage, means for driving the carriage from said shaft, a sintering pan cover suspended in the carriage, and mechanism actuated from said shaft to move the cover, a louver bottom for the cover, mechanism actuated from said shaft for moving the bottom, an air tank and an oil tank on the carriage, said oil tank maintained under air pressure from the air tank, a burner on the cover and means to supply oil and air from said tanks to the burner.

9. In combination, a cover having means for supporting a charge of material therein, wheeled means for supporting the cover, means for moving the cover onto and from a sintering pan after the cover has been placed over such pan, and means for operating said material supporting means to discharge into such pan.

10. In combination, a traveling receptacle, means therein to support a charge of material to be sintered, means to move said receptacle onto and from a sintering pan and means to discharge the receptacle, said receptacle operating to cover a sintering pan during initiation of the sintering.

11. The combination with a sintering pan, of a car having a body to cover said pan, a burner depending within the body above the pan, means to supply said burner with combustible and combustion air, and means in the body to support a charge for the pan and supply it thereto to controllably supply combustion air to a charge after it has been deposited in said pan.

12. The method of charging pans for sintering fines, which comprises forming a body of the material to be charged of uniform thickness, sub-dividing the charge and dropping the subdivisions simultaneously into the sintering pan.

13. The method of charging pans for sintering fines which comprises forming a body of the material to be charged of uniform thickness, then subdividing the body into

parallel portions and dropping such portions simultaneously into the sintering pan.

In testimony that we claim the foregoing as our invention, we have signed our names in presence of two subscribing witnesses.

FRANK D. CARNEY.
